[57] CLAIM

The ornamental design for a barrier post, as shown and described.

DESCRIPTION

FIG. 1 is a frontal perspective view showing my novel barrier post design, which can be used, for example, at the beginning of or along pedestrian walkways to block access by vehicles, whereby if used along a walkway the barrier posts could even be linked by a cable or chain;

FIG. 2 is a front view with the rear view being identical thereto;

FIG. 3 is a right side view thereof with the left side view being identical thereto;

FIG. 4 is a bottom view thereof;

FIG. 5 is a top view thereof;

FIG. 6 is a frontal perspective view showing an alternative embodiment of my novel barrier post design;

FIG. 7 is a front view thereof with the rear view being identical thereto;

FIG. 8 is a right side view thereof with the left side view being identical thereto;

FIG. 9 is a bottom view thereof; and,

FIG. 10 is a top view thereof.
